ABSTRACT OF THE DISCLOSURE

The spinning machine includes an automatic device for binding broken yarns. The device includes a detector which senses the occurrence of a broken yarn as well as a continuously movable belt for taking up a broken yarn end. The spool upon which the broken yarn is, is extracted from rotation engagement with a spindle after detection of a broken yarn to permit binding of the broken ends.

This invention relates to an automatic apparatus for binding broken yarns on spinning machines.

Heretofore, whenever a yarn was broken during operation of a spinning machine it was necessary for an operator to detect the broken yarn, shut off the appropriate parts of the machine, and manually bind the broken ends of the yarn. This, of course, is not only time consuming and expensive but also does not provide an instantaneous manner of detecting a broken yarn.

Accordingly, it is an object of this invention to provide an apparatus for binding broken yarns on spinning machines which is automatic.

It is another object of this invention to provide an apparatus which automatically detects a broken yarn in a spinning machine.

It is another object of this invention to provide an apparatus which automatically halts continued yarn spinning upon breaking of a yarn in a spinning machine.

It is another object of this invention to reduce the shut down time of a spinning machine caused by broken yarns.

It is another object of this invention to reduce the cost of binding the broken ends of a yarn in spinning machines.

It is another object of this invention to provide an apparatus for binding broken yarns in a smooth operation.

Generally, the apparatus of this invention includes a carriage which is reciprocally mounted along a path parallel to a row of spindles of a spinning machine. The carriage provides a mount for various units for mechanically performing the various movements and operations required for detecting and binding any broken yarns. In addition, the apparatus includes a programming memory for actuating the units in synchronization according to a predetermined set of controls of an operation cycle.

The units mounted on the reciprocal carriage includes a vertically reciprocal support; a sensing unit for detecting a broken yarn; a unit for halting the operation of the apparatus at the spindle where a broken yarn is detected; a spool extraction unit for removing the spool of broken yarn from the spindle; a spool height sensing unit for

2

positioning the apparatus with respect to the spool; a searching unit for taking up a broken yarn end; a traveller searching unit for positioning a traveller at a predetermined position on a guide track of the machine; a threading unit for threading yarn into the traveller; and a unit for binding yarn and cutting excess portions.

These and other objects and advantages of the invention will become more apparent from the following detailed description and appended claims taken in conjunction with the accompanying drawings in which:

FIG. 1 is a general front view of the apparatus according to the invention;

FIG. 2 is a general top view of the apparatus;

FIG. 3 is an elevational view of the unit for halting the apparatus at the spindle where broken yarn is detected;

FIG. 3A is a top view of the halting unit of FIG. 3, when approaching a spindle;

FIG. 3B is a top view similar to FIG. 3A, however showing the halting unit in halt position against a spindle;

FIG. 4 is a schematic lateral view of the sensing unit for detecting a broken yarn;

FIG. 4A is a partial front view of a detail of FIG. 4;

FIG. 5 is an elevational sectional view of the unit for extracting a spool from a spindle and for causing opposite rotation of said spool, with extraction pincers in release position;

FIG. 5A is a view similar to FIG. 5, but showing the pincers in expanded gripping position;

FIG. 6 is a top view of the spool height sensing unit;

FIG. 6A is a side view of the spool height sensing unit of FIG. 6 in a first down stroke stage;

FIG. 6B is a side view like that of FIG. 6A but in a second down stroke stage;

FIG. 7 is a diagrammatic side view of the searching unit for broken yarn ends in a position remote from a spool;

FIG. 7A is a side view similar to FIG. 7, with the unit in search position on a spool;

FIG. 7B is a top view showing operation of unit of FIGS. 7 and 7A;

FIG. 8 is a top view of the traveller searching unit on the guide track of the spinning machine, in a remote position from the track;

FIG. 8A is a top view similar to FIG. 8, but with the unit in traveller search position;

FIG. 8B is a sectional side view of unit of FIGS. 8 and 8A;

FIG. 9 is a diagrammatic side view of the threading unit for threading yarn into the traveller, in a position remote from a ring guide track;

FIG. 9A is a view similar to FIG. 9 but with the unit in operative position on the guide track;

FIG. 9B is a front view, taken at an angle of 90 degrees in respect to FIGS. 9 and 9A, showing an operative detail of the unit;

FIG. 10 is a side view showing a first embodiment of a unit for binding and cutting yarn in an inoperative position;

FIG. 10A is a view similar to FIG. 10, but with the unit for binding and cutting yarn in operative position;

FIG. 11 is a top view of the head of the binding and cutting device of FIG. 10, with cutting shears in open position;

FIG. 11A is a top view similar to FIG. 11, but with the cutting shears in closed position;

FIG. 12 is a side view of a second embodiment of a unit for binding and cutting yarn, while advancing toward the binding position;

FIG. 13 is a top view of the unit of FIG. 12;

FIG. 14 is a side view of FIG. 12, illustrating the binding and cutting unit in binding and cutting position;

FIG. 15 is a top view of the unit of FIG. 12, in the same position shown in FIG. 14;

FIG. 16 is a diagrammatic, partially sectioned side elevational view of a third embodiment of a unit for binding and cutting yarn, in operative position;

FIG. 17 is a top view of the unit of FIG. 16, with cutting blades in open position; and

FIG. 18 is a top view like that of FIG. 17, but with cutting blades in the closed position.

Reference will now be made to the accompanying drawings for a full illustration of construction and operation of the apparatus according to the present invention, in which drawings many mechanical parts known per se were diagrammatically shown, and in the figures illustrating the various units, such units were separately shown for making easier reading of the drawings, removing interference of adjacent units.

Referring to the drawings wherein mechanical parts known per se are diagrammatically shown and wherein the various units of an apparatus of the invention are separately illustrated for facilitating the description of the apparatus.

Referring to FIGS. 1 and 2, the apparatus according to the invention travels reciprocally back and forth along a spinning machine by means of wheel 1 running on track 2. When forward travel of the apparatus is over, a limit switch (not shown) provides for reversing the rotation of a motor 3. The reciprocal travel of the apparatus is even and continuous and halting of the apparatus in a determined position on a spindle occurs if and when one of the two sensing devices 4 or 4', according to the direction of travel, senses a lack of yarn and therefore it breaks and gives a suitable halting signal.

The yarn binding apparatus of the invention is practically comprised of the following units:

A pneumatic memory 5, which could also be electric or electronic, having the object of giving several predetermined controls, in order to cause the operative cycle to take place in an exactly programmed way.

A vertically reciprocable support 6 bearing other units for searching and binding the broken yarn which is controlled by a piston 8 and slides vertically on column 7.

A spool extraction unit 9 which rotates a spool in a direction contrary to the normal direction of rotation of spinning.

A traveller searching unit 10 (FIG. 2) having the object of finding a traveller on an annular guide track and positioning it in a fixed manner, that is to say in a fixed position.

A unit 11 having the object of threading a broken yarn into the traveller found by unit 10.

A unit 12 having the object of halting the apparatus when a broken yarn is found.

A compressed air pipe 13 bearing one valve 14 at each spindle where the apparatus takes air when stopping by means of a joint 15.

The apparatus also has a two-way aspirator.

Operation of the apparatus is described below by description of the operations of each of its various units.

Sensing of broken yarns is made in advance since the apparatus senses an eventual lack of yarn before the units designed for its binding reach the operative position. In fact, other units of the apparatus are located in a central position with respect to a spindle on which is positioned a spool 17, whilst sensing devices 4 and 4' are advanced, to the left or to the right of said spindle, according to the travel direction of the apparatus.

The object of this advanced sensing operation is to obtain a smooth halt, and to avoid dashes and sudden blows.

Besides being advanced, sensing of the lack of yarns provides another function which occurs in the following manner:

At each of points 18 and 18' (FIG. 1) there is a pneumatic valve which is opened upon contact for a fraction of a second with a leg 19, 19' of a respective spindle, or with pins arranged at a length equal to a spindle's center distance. These valves communicate with a little reservoir of compressed air (not shown).

When either of the valves at 18 or 18' is opened after contacting the leg 19, 19' of a spindle, a little amount of air is delivered to sensing device 4 or 4', which has to indicate whether or not there is a broken yarn in that position. The sensing control is thus dual, since the sensing device 4 or 4' is operative only when it is in front of a yarn. In fact between two subsequent yarns there is void space, and if the sensing device would operate in this space, it would always indicate lack of yarn, thus making an error. With dual control valve 18 or 18' giving a signal of proper position, the sensing device 4 or 4' operates only when it has been positioned.

Of course, this dual detection could also be electrical, magnetic or electro-pneumatic, in this case a pneumatic system was preferred because it is more efficient as to wear.

Sensing devices 4 and 4' operate in the following manner (FIGS. 4 and 4A):

Referring to FIG. 4, the little blow of compressed air from valve 18 impacts on a light swinging blade 33 which, being balanced on pin 34, is moved forward by air with a certain force; if this blade finds in front of itself a yarn, it makes a very little stroke up to yarn 35 which stops it; on the contrary if the yarn is broken, blade 33 makes its complete and wider swinging stroke and with its lever arm 36 gives a pulse to microswitch 20.

When blade 33 has given a mechanical pulse to microswitch 20 because of a lack of yarn, the microswitch 20 electrically feeds its control to unit 12 in order to halt the apparatus in the proper position.

This unit 12 operates as follows (see FIG. 3):

Pulse from microswitch 20 causes operation of electromagnet 21, which pushes a saddle 22 forward causing Y-shaped rod 23 to extend into the axis of the spindle's support. The apparatus continues to travel but when rod 23 comes into contact with spindle 24, such a contact causes an angular movement of the rod 23, which will stop against grip 25, so as to block advancement of the apparatus.

On the grip 25 there is also placed an electric microswitch (not shown), which when touched by rod arm 23, will cause stoppage of the motor 3 and engagement of filling union 15 on valve 14 (FIG. 1). This engagement provides for inlet of compressed air in the pneumatic circuit of the apparatus of the invention and therefore provides also for recharge of supplemental reservoir which is not shown in the figures and has the purpose of feeding the sensing device or yarn detector 4-4'. At the same time (see FIG. 3) cam 26 raises a brake or friction clutch 27 and stops the rotary motion of the spindle. The extraction unit 9 (FIG. 1) is instantly actuated in order to raise the spool and impart to the spool a rotary motion in a direction contrary to that of the spool during the normal working cycle. The extraction operation occurs in the following manner as illustrated in FIGS. 5, 5A, 1 and 2:

Piston 28 pushes the end of assembly 29 outwardly so as to exactly center it over the axis of the spindle where the yarn is broken. Piston 30 lowers the whole assembly 29 and causes expandable pincers 31 to thread on cop of spool 17. Then (see FIG. 5) a pneumatic piston inside assembly 29 causes expansion of the pincers 31 thereby causing the cop 32 of spool 17 to become engaged (FIG. 5A) with the assembly 29 so that cop 32 is fixed at the upper end

to the assembly 29 while the steel spindle still remains within the lower end of the cop, however disengaged therefrom. As the piston 30 thereafter rises, it carries the cop 32 with it.

At this moment motor 37 starts to rotate and transmits through a belt its motion to assembly 29 which in turn starts to rotate in a direction opposite to the direction of rotation of spindles; as the spool is fixed to this assembly, it acquires a rotation contrary to its normal working rotation. At this moment, piston 8 (FIG. 1) is actuated and lowers the support 6 which is rather complex since it has to carry out several operations.

The first of said operations is the following: a piston 38 pushes a rod (not shown) against column 7; when the support 6, moving downwards, reaches position 39 the aforementioned rod enters notch 39 causing a stop in the downward movement of the support 6. When the support 6 is stopped, the sensing unit for locating the exact position of the support 6 with respect to the spool is actuated, as viewed in FIGS. 6, 6A and 6B. A fork 40 embodied in the support 6 and controlled by the memory 5 engages the cop 32 between its prongs.

When fork 40 has engaged the cop, the memory 5 will again actuate the piston 38 (FIG. 1) and will retract the rod which had stopped with its insertion into notch 39 upon initial lowering of support 6, so that the whole support 6 will again slide downwards. At a certain point fork 40 will touch the spool of yarn at position 41 and will be stopped from further movement down the cop. It is noted that the lever or fork 40 is adjusted by means of springs 42 and 43 so as to be capable of overcoming the natural smooth friction of cop 32, but not the greater friction of yarn. The support 6 still proceeds slowly downwards, so that lever or fork 40 will start to rotate about its fulcrum 44, until at point 45 it makes contact with microswitch 46. The microswitch 46 controls an electromagnet 47 (FIG. 1) which acting on lever arm 48, through a rotary eccentric pivot, will block support 6 in this position stopping its lowering.

In view of the fact that a cop winds on itself yarn at positions which are gradually varying from top to bottom, the position of support 6 in respect to the spool may be different according to the working stage (e.g. about full spool, half spool, about empty spool).

At this moment support 6 is positioned for carrying out a yarn search. A searching unit for the search of broken yarn is mounted on support 6 and operates as will be now explained, and as shown in FIGURES 7, 7A and 7B.

The search unit includes a flat suction tube 49, a pneumatic turbine 50, a transmission 51, and a belt 52; this search unit when the apparatus is travelling, as shown in FIG. 7, is spaced apart from the spool 17. A piston controlled by memory 5 pushes the search unit comprising the suction tube, turbine and belt, toward the spool (FIG. 7A) so that the transmission 51 proceeds beyond the spool. Upon continued travel, cam 53, coming into contact with roller 54, compels the transmission and belt 52 to move toward the spool 17 (FIG. 7B) through the angular movement of lever 54. In this manner, suction tube 49 will stop close to the spool with the belt 52 in contact with the yarn wound on the conical part of the spool. At this moment, spool 17 is already rotating on the direction opposite to its normal rotation on the spindle, so that for the search of broken yarn three elements are combined, namely: a rotary motion contrary to that of spindle, a friction of belt on spool in the direction opposite to spool rotation, and air aspiration. Pneumatic turbine 50 causes belt 52 to rotate at a speed which is many times greater than the maximum peripheral velocity of spool 17, so that the end of a broken yarn, which is surely located between points 55 and 56, comes in contact with the soft belt and is drawn back toward position 57. Because the belt velocity is greater than the yarn unwinding speed, the end of the broken yarn slips from the belt and is taken up by suction tube 49 (aspirator). The suction tube 49 when it

has taken up the yarn end continues to pick up yarn whilst spool 17 is rotating, so that the tube 49 will store a certain amount of yarn as it is fed into the suction tube.

The suction tube 49 has not only to pick up the end of yarn, but also to store a certain amount of yarn at least equal to the distance between bottom of the spindle and the roving feeding rollers. Spinning frames are in fact a unique kind of device in the field of textile machinery, wherein it is required to bind two different elements, that is, an already twisted yarn with a roving which will become yarn when receiving twists. Since it is not possible to draw roving away from feeding rollers, as it would without a doubt break, it is necessary to have a sufficient length of yarn for carrying its end up to the roving feeding rollers. It is therefore indispensable that the suction tube store a certain length of yarn. Since in tube 58 the air whirls created by suction have a tendency to cause yarn to lose twists, as those latter are not yet set the tube 58 is given an undulated shape, so that the yarn will have several points of contact with the tube, e.g. points 59-59'-59'', which are sufficient for hindering unwinding of yarn under suction air whirls; of course, such a shaping of the tube 58 could also be carried out in other ways without departing from spirit of the invention. The principle is that of creating contact points within suction tube 58 in order to retain yarn against countertwisting.

When the suction tube 49 has picked up a sufficient length of yarn, the whole support 6 returns to the position shown in FIG. 7 and turbine 50 is stopped.

Piston 30 (see FIG. 1) is lowered and brings back cop 17 in its position anchored to the spindle; pincers 31, operated by the internal piston, are detached from the cop, piston 30 causes the assembly to rise again and piston 28 brings unit 9 back to the inoperative position of FIGS. 1 and 2.

At the same time a search is performed for the traveller 60 (FIG. 2), which may still be in any position on an annular track 61 and which has to be placed in a fixed position in order to allow yarn to be threaded thereinto; such a search takes place as follows (FIGS. 8, 8A and 8B):

Two rollers 63 and 63' bearing a swinging support 64 are placed over the table 62 of the spinning frames (FIGS. 1 and 2), which has, as it is well known, a reciprocated swinging vertical movement in order to store yarn on a spool. The rollers 63 and 63' (FIG. 2) follow the up and down movement of the table 62, and on their support 64 there is mounted a unit providing for the search of the traveller (FIG. 8). A piston 65 is mounted on support 64 which through a rod 66 actuates a movable support 67. On this movable support 67 there are suitably shaped little air nozzles 68 having the object of finding the traveller. When it is required to search for the traveller, memory 5 gives an impulse to piston 63; rod 66 pushes the whole support 67 with nozzles 68 onto table 62, so that the nozzles are placed in such a way that a supply of compressed air is delivered to said nozzles to create an air stream which is circular and tangential to traveller guide track 61; traveller 70, which may be located in any point of this track, is struck by these air blows and caused to rotate. However, when the traveller 70 reaches pin 69, it is stopped against outer surface of track 61, as pin 69 does not allow further rotation of the traveller. This halt position is that fixed for threading yarn onto the traveller; it is, however, necessary to halt the traveller in a safer manner in order to avoid vibrations or impacts which displace the traveller from the fixed position. For such a locking of the traveller there is provided a piston 71, which, as it is best shown in FIGURE 8B, is fixed on support 64 but is not bound to back and forth movement of piston 65. This piston 71 pushes under traveller 70, through rod 72 and lever 73, a spring 74 having the form of a seat. The spring 74, when coming into contact with the traveller, locks it, hindering any further move-

ment thereof. At this moment memory 5 causes the piston 65 to draw back the unit and terminate the air blows of nozzles 68 so that the traveller will be held only by members 71-72-73-74, which are not moving.

Unit 11 is now actuated in order to thread yarn into the traveller 70. Such a unit 11 operates in the following way, illustrated in FIGS. 9, 9A and 9B.

It is to be pointed out that yarn, which has been found and is still retained in elastic fashion by suction tube 49, passes through pigtail 75 of spinning machine and reaches spool 17. The fact that yarn is threaded into pigtail 75 is due to the reason that since the spool 17 is raised by the spool extraction unit 9 and brought away from the pigtail the return of the spool to its original position will cause the yarn retained by the aspirator 49 to be automatically placed inside the pigtail.

The threading unit 11 for threading yarn into the traveller is secured to the support 64 and therefore follows the vertical up and down movement of the table of the spinning frame (see FIG. 9). A piston 76 through rod 77 raises group 78 above pigtail 75; then piston 79 pushes the whole group 78 to the left so that projection 80 enters the path of the pigtail; then piston 76 causes the whole group to return downwards, but projection 80 meeting pigtail 75, will stop group 78 at the level of the pigtail (FIG. 9A). This operation is necessary since pigtail has a reciprocating swinging vertical movement and threading of yarn into the traveller is bound to the position of the pigtail.

As projection 80 stopped on pigtail 75, piston 81 will move needle 82 to a position which is just under pigtail 75, so that such a needle 82 will surely be in a position between cop and yarn which is fed with a certain elastic tension on the pigtail due to the suction tube. At this moment piston 83, always controlled by the memory 5, will perform an angular downward movement so that the piston will reach position 81' and needle the position 82".

Then memory 5 actuates piston 81 causing it to return and needle 82 will drag yarn compelling it to pass under traveller 70 which will capture and hook the yarn.

As yarn is captured by the needle 82 and is threaded under traveller 70, piston 71 (FIG. 8B) during its return stroke will leave traveller free. At this moment support 6 (FIG. 1) again moves upwards being pushed by piston 8, dragging aspirator 49 and sucked yarn.

The automatic apparatus according to the present invention, according to the kind of fibers or thickness of yarns to which it is destined, may be provided with one of the three units for binding yarn mounted on the support 6 which will be hereinafter disclosed.

It is to be understood that each of these three embodiments of the unit for binding broken yarn, to be now described, is universal, that is to say it may be applied for any kind of fiber or spun yarn, but each of these embodiments yields an optimum operation of invisibly binding roving and yarn, when particularly utilized with a certain kind or class of fibers or yarns.

As a general but not limiting rule, the binding unit described and illustrated with reference to FIGURES 10, 10A, 11 and 11A is the best when used particularly for long fibers and very thin yarns.

The binding unit described and illustrated in FIGURES 12, 13, 14 and 15, is particularly suitable for its binding quality with short or middle fibers and with thick yarns.

At last, the binding unit described and illustrated in FIGURES 16, 17 and 18, is however very good with any kind of fibers but is scarcely suitable for binding thick yarns.

Making first reference to FIGURES 10, 10A, 11 and 11A, wherein the first embodiment of the binding group is illustrated in FIG. 10, the yarn is clearly shown held by suction tube and threaded into traveller 70. Binding of the yarn takes place as follows electromagnet 21 which, as indicated in FIG. 3, had pushed cam 26 acting against friction clutch 27 for halting the spool is locked and a

spring provides for moving the unit 12 away from spool 17, so that the spool 17 is again put into rotation. At the same time (see FIG. 10A) piston 86 controlled by the memory 5 pushes assembly 85 through rod 87 toward roving feeding rollers 88-89 which are feeding roving 90 which is absorbed, when the yarn is broken, by the conventional aspirator 91 of the spinning machine.

Assembly 85 has a V-shaped end portion (see FIG. 11) so that on forward movement under piston 86, it takes 10 yarn extending from traveller 70 to suction tube 49 and brings it automatically into a control position up to position 92. At this moment shears 93-93' are open; when piston 94 controlled by memory 5 pushes cam 95, the ring cam 95 acts on lever arms 96-96' to transmit movement 15 to shears 93-93' to meet the roving 90, cut it and contemporaneously close or interrupt aspirator inlet 91 with the surface of their blades (FIG. 11A).

Another aspirator 97, placed just under assembly 85, 20 sucks and retains roving cut by shears 93. At the same time movement of cam 95 also causes closures of shears 98-98' by means of pressure exerted by the levers on buttons 99-99'. The yarn which is thus cut between shears 98-98' is the yarn extending from V center to suction tube 49. All of the useless yarn extending between the cut 25 made at point 99-99' and suction tube 49, is absorbed by suction tube 49 itself and brought to a recovery box. At the same time a piston 100 is actuated which through rod 101 acts on rocking lever 102 and causes arms 103 and 103' to move in opposite direction; the arms 103- 30 103' having moved close to one another when button 99-99' exerted a pressure for actuating shears 98 and 98'. Summarizing, the following movements occur contemporaneously; shears 93 cut roving 90 absorbed by aspirator 91; yarn is cut and the exceeding portion is 35 sucked and recovered by suction tube 49. Yarn and roving are kept between arms 103-103' which, being lined of high friction material, and being put into movement of opposite directions, compel yarn and roving to join and kink slightly together because of frictional rubbing. However, when cam 95 during its stroke, because of its 40 particular shape in the form of double wedge, reaches end of said stroke, shears 93 are again opened by means of a return spring; the two rubbing arms 103-103' are moved away from one another so that yarn bound to roving is now completely free. At this moment twists imparted by 45 spool 17 duly reach the binding point between yarn and roving, so that roving fed by feeding rollers 88 and 89 takes the usual twist and therefore acquires consistency becoming yarn. Then piston 86 causes group 85 to return and a microswitch not indicated in the figures, causes 50 disengagement (see FIG. 1) of electromagnet bearing joint 15, which disengages air intake and the same microswitch causes actuation of motor 3, so that the apparatus of the invention travels again for detecting other broken yarns.

Reference is now made to FIGURES 12-15 for the description of the second embodiment of yarn binding unit.

Support 201 is pneumatically driven, e.g. by means of a cylinder and piston system like that of the first embodiment, and is moved toward rollers 88 and 89 feeding 60 roving 90.

During such a movement roller 203 impacts against feeding roller 89 causing rotation of lever 202 having a fulcrum at 216, the rotation being limited by engagement of the tail 202' of lever 202 against projection 204 which is provided with a precise adjustment screw.

Advancement of support 201 and rotation of lever 202 65 result that at the end of a stroke the unit is in the position indicated in FIG. 14, that is roller 205 comes into contact with feeding roller 89 which in this way transmits its rotary motion with about equal peripheral velocity to roller 205 and thence is transmitted in turn to cylinder 206. Yarn 84 coming from the spool and having its 70 broken end held by suction tube 49, although cylinder 75

206 rotates, is not drawn because it is free and therefore only slides on cylinder 206.

At a certain moment cam 212, pneumatically controlled by a piston rod 214 arranged within the support 201, comes into contact with control rollers 213 of lever arms 219 which bear at their ends a roller 209 and shears 208 for engaging and cutting roving 90.

Upon closure, shears 208 cut roving 90 which is sent by shears 208, whilst being fed by feeding rollers 88 and 89, toward rotating cylinder 206.

While shears 208 are closing, roller 209, which when shears were open did not touch cylinder 206, comes into contact with said cylinder 206 and making a pressure thereon presses yarn 84 and feeds it downwards, that is toward the spool.

Yarn 84 begins to receive twists imparted from spool (not shown) which started to rotate.

Roving 90 coming into contact with yarn 84 on the tangential line of contact between cylinder 206 and roller 209 (FIG. 14), will amalgamate with the yarn itself as an effect of twists coming from bottom.

Shears 208 are again opened and roller 209 will be moved laterally so that spool will transmit its twists directly to roving now bound to yarn which was broken, causing said roving to become yarn.

Other not shown shears, controlled through rollers 210 by a second cam 215 of piston rod 214, will provide a means to cut the exceeding yarn 84 which was retained by suction tube 49, the exceeding portion of yarn being then absorbed by such a suction tube 49 and sent to discharge.

It is to be noted that shears 208, when they are closed, cut roving 90 but not yarn 84, which of course has to remain integral for amalgamating to the roving, because blades of shears 208 are provided with a reentrant portion 217 which, when shears 208 are closed, form an opening 218 allowing passage of yarn 84 held between cylinder 206 and roller 209.

Finally, referring to FIGURES 16-18, there will now be described the third embodiment of the yarn binding unit.

Broken yarn 84 (shown with dotted lines in FIGS. 16 and 17) coming from spool 17, already threaded into traveller 70 and pigtail 75, passes through a tube 302 provided with a cut slit 303 into the suction tube 49 which holds it in an elastic manner.

Feeding rollers 88 and 89 continuously supply roving 90 which is sucked (when yarn is broken) and discharged by a conventional aspirator 91 of the spinning machine.

When it is desired to provide for binding yarn 84 with roving 90, the binding unit of the invention actuated to move toward the operative position by any suitable and not shown means.

Shears 311 are closed and cut roving 90. An air blow coming out from pipe 312 acts on roving 90 and pushes it through slit 303 of tube 302, inside tube 302 itself.

Another air blow, coming out from pipe 316, having its outlet at the top of tube 302, feeds air within tube 302 producing a circular air whirl so that roving 90 kinks (see FIG. 16) on stretched yarn 84. This air whirl is obtained either by suitably shaping the outlet of pipe 316 in tube 302 in such a way that the air blow enters tube 302 in a direction oblique and tangential to the inner wall of tube 302 or by providing an internal helical or screw shaping (not shown).

At this moment shears 315 cut the yarn for avoiding an excessive length of junction and the tension given by rotation of spindle 17 causes yarn 84 to be wound on a spool and roving, again making connection of the roving with the spool and therefore the normal spinning operation. After shears 315 have cut yarn 84, the exceeding portion of yarn is absorbed by the suction tube 49.

Operation of the above said members is better seen from FIGS. 17 and 18 where controls for said members are illustrated in detail.

In FIG. 17, the unit is shown just before operation; shears 311 are open and pipe 312 is external to the unit; also shears 315 are open and pipe 316 is not fed with air.

Tube 302 has a front slit 303 allowing, when the shears are open, introduction of yarn 84 into tube 302.

Another important feature is that curve 317 of the central portion of shears 311 allows the shears to close even in presence of the central tube 302.

In FIG. 18 the unit is shown during cutting operation. A rod 307, controlled pneumatically or in other suitable manner, has end cams 308 and 309.

The first cam 308 actuates levers 310 causing closure movement of shears 311. At the same time pipe 312 is centered in front of shears 311 and can push roving 90 to point 313 inside tube 302 in view of slit 303, keeping the roving 90 under tension.

Air is fed to pipe 316 and thence inside tube 302 producing the circular whirl for binding yarn 84 with roving 90.

Immediately thereafter, cam 309 through lever 314 actuates shears 315 through which yarn 84 passes, cutting it and completing operation.

At the end of the stroke, cams 308 and 309 allow levers 310 and 314 to return to the position of FIG. 17, thus causing both shears 311 and 315 to open again in order to avoid imprisonment of the yarn 84 in the closed shears so that when the unit is moved away, the bound yarn is free and comes out from tube 302 through slit 303.

Having thus described the invention, it is not intended that it be so limited as changes may be readily made therein without departing from the scope of the invention. Accordingly, it is intended that the subject matter described above and shown in the drawings be interpreted as illustrative and not in a limiting sense.

35 What is claimed is:

1. In combination with a spinning machine having a longitudinally aligned row of spindles, a plurality of spools rotatably mounted on said spindles, a reciprocal vertically movable table including a plurality of traveller guide tracks, each of which surrounds one of said spools and a traveller movably mounted on each of said guide tracks, a plurality of pigtailed each of which is reciprocally mounted over one of said spools, a plurality of roving feed rollers mounted over said pigtailed, and an air supply source having intakes arranged at intervals equal to the center distance of said spindles; an automatic apparatus for binding broken yarns, said apparatus comprising a carriage mounted for reciprocal movement along a path parallel to said row of spindles, said carriage having mounted thereon a halting unit for detecting broken yarn, a halting unit for halting the operation of said apparatus upon detection of a broken yarn, a spool extraction unit for removing a spool from rotational engagement with a spindle, a spool height sensing unit for locating the position of a spool, a yarn searching unit for taking up the end of a broken yarn on one of said spools, a traveller searching unit for positioning said traveller at a predetermined position on said guide track, a threading unit for threading the broken yarn into said traveller, a unit for binding the broken end of a yarn to the end of a roving and for cutting the excess portions thereof, and a cycle programming memory for synchronizing the operation of said units.

2. The combination as set forth in claim 1, wherein said broken yarn sensing unit is arranged in advance of said units for searching and binding yarn.

3. The combination as set forth in claim 2, wherein said broken yarn sensing unit is comprised of a positioner for actuating said broken yarn sensing unit when said broken yarn sensing unit is in front of a point where a yarn should be located.

4. The combination as set forth in claim 3, wherein said positioner includes an air blow valve and said broken yarn sensing unit further comprises a swingable blade positioned at one end of said air blow valve whereby said

blade is pushed toward yarn by an air blow fed under control of said positioner upon actuation of said broken sensing unit so that in the event of lack of yarn said blade is adapted to rotate to a position to actuate a switch for actuating said halting unit.

5. The combination as set forth in claim 1, wherein said halting unit comprises a slidable saddle having a rotatable rod mounted thereon for movement into the plane of said row of spindles and a grip mounted thereon for contacting said rod upon rotation thereof whereby a signal is actuated upon contact of said rod and grip to cause a smooth halt of said apparatus.

6. The combination as set forth in claim 5, which further comprises a compressed air picking valve for insertion into air contact with said intakes of the air supply source of the spinning machine upon contact of said rod with said grip.

7. The combination as set forth in claim 5, wherein said halting unit further comprises a friction clutch for braking and stopping rotary motion of a spindle upon sensing of a lack of yarn.

8. The combination as set forth in claim 1, wherein spool extraction unit comprises expandable pincers for lowering within the cavity of a spool cop, means for expanding said pincers into engagement with said cop, and means for subsequently raising said spool from rotational engagement with its respective spindle.

9. The combination as set forth in claim 8, wherein said spool extraction unit further comprises means for imparting a slow rotary motion to said pincers in a direction opposite to the normal direction of rotation of spindles on said spinning machine so as to cause unwinding of an amount of yarn from said spool which is at least sufficient to reach the roving feeding rollers of the spinning machine.

10. The combination as set forth in claim 1, wherein the spool height sensing unit comprises a microswitch and a pivotal fork, said fork having one end for threading on a spool cop and sliding down said cop to the top of wound yarn spool, and an opposed end for contacting said microswitch at a predetermined point of rotation whereby said microswitch activates said yarn searching unit upon contact with said fork.

11. The combination as set forth in claim 1 wherein said yarn searching unit includes a continuous belt for contacting the side of a spool, said belt being movable in a direction opposed to the movement of a spool of yarn at a greater than said spool for taking up the broken end of the yarn on said spool, a means including a turbine and transmission for moving said continuous belt, and a suction tube having an outlet positioned adjacent said belt and spool for sucking in an elastic manner the broken end of the yarn to a length sufficient for binding.

12. The combination as set forth in claim 11 wherein said suction tube has an undulated shape for preventing untwisting of the yarn by air whirls.

13. The combination as set forth in claim 1 wherein said traveller searching unit is mounted in synchronism with said reciprocal vertically movable table of said spinning machine to follow the movement thereof and includes a horizontally reciprocal support for enveloping a spool, a plurality of air nozzles mounted on said support in operable connection with said air supply source of the machine for directing tangential air streams toward said traveller guide track to move said traveller around said traveller guide track, a pin mounted on said support for projection into the path of said traveller to stop the movement of said traveller at said predetermined point, and a spring means mounted on said support for locking said traveller at said predetermined point.

14. The combination as set forth in claim 1 wherein said threading unit is mounted in synchronism with said reciprocal vertically movable table of said spinning machine to follow the movement thereof and includes a horizontally movable projection for engaging a pigtail to

stop movement of said threading unit at the level of said pigtail, a pivotal needle positioned below said projection for capturing yarn upon a downward movement, and for threading a captured yarn into said traveller upon an upward movement, and means for pivoting said needle.

5 15. The combination as set forth in claim 1 wherein said unit for binding is mounted in a plane between said pigtail and said roving feed rollers and includes a horizontally movable assembly having a forward V-shaped end portion for moving a broken yarn end to a control position, a first pair of shears for cutting a length of roving from said feed rollers, a second pair of shears for cutting a length of yarn from the broken yarn end, means for actuating each of said pair of shears, a pair of oppositely movable arms for engaging a broken yarn end and roving end therebetween, and means for moving said arms in opposite directions for joining the yarn and roving together.

10 16. The combination as set forth in claim 15 wherein the engaging surfaces of each of said arms is lined with high friction material.

15 17. The combination as set forth in claim 15 wherein said unit for binding further includes an aspirator for absorbing the uncut length of roving.

20 18. The combination as set forth in claim 1 wherein said apparatus further includes a vertically movable support mounted in synchronism with said reciprocal vertically movable table to follow the movement thereof, said movable support having said spool height sensing unit, 25 yarn searching unit, traveller searching unit, threading unit and binding unit mounted thereon for vertical movement therewith.

25 19. The combination as set forth in claim 1, wherein said cycle programming memory is a pneumatic memory.

30 20. The combination as set forth in claim 1 wherein said unit for binding includes a horizontally movable support for movement towards said roving feed rollers to engage a yarn extending into said yarn searching unit at an intermediate point thereof, a lever pivotally mounted 35 on said horizontally movable support, said lever having a first arm for imparting against one of said roving feed rollers to pivot said lever, a pair of rollers mounted on said support for rotatably engaging said one of said roving feed rollers, rotatable cylinder mounted on said lever for rotatably engaging said pair of rollers, a pair of cutters pivotally mounted on said lever for cutting a length of roving from said feed rollers, one of said cutters having a roller mounted at the end thereof for pivoting into rotatable engagement with said rotatable cylinder, and means for moving said cutters together whereby the uncut length of the roving and the broken yarn end are engaged between said rotatable cylinder and said roller for amalgamation.

40 21. The combination as set forth in claim 20 wherein 45 said cutters have a central reentrant portion which during closure forms a passage for yarn which is not being cut.

45 22. The combination as set forth in claim 1 wherein said unit for binding includes a horizontally movable support having a V-shaped forward portion for guiding an intermediate portion of a yarn extending into said yarn 50 searching unit and a roving therein, a tube located in said support, said tube having a slit in the wall thereof for communication with the exterior of said forward portion of said support, a first pair of cutters pivotally mounted around said tube for cutting a length of roving from said feed rollers, a first air pipe for expelling an air stream through said slit, a second air pipe for directing an air stream into said tube to produce a circular air whirl therein, a second pair of cutters for cutting a length of yarn from the broken yarn end, and means for actuating said first and second pair of cutters in a time spaced sequential order whereby a yarn and roving within said tube are twisted together.

55 23. The combination as set forth in claim 22 wherein

said actuating means comprises a double cam having a shape to open said first and second cutters immediately after cutting operation whereby the bound yarn is free to escape from said binding unit for continuation of the spinning operation.
